UNITED STATES PATENT OFFICE.

JOHN J. ALVORD, OF BRIDGEPORT, CONNECTICUT.

DESIGN FOR A MEMBER FOR PAIRS OF SHEARS.

SPECIFICATION forming part of Design No. 32,084, dated January 9, 1900.

Application filed November 4, 1899. Serial No. 735,837. Term of patent 7 years.

To all whom it may concern:

Be it known that I, JOHN J. ALVORD, a citizen of the United States, and a resident of Bridgeport, in the county of Fairfield and State of Connecticut, have invented and produced a certain new and original Design for a Member of a Pair of Shears, of which the following is a specification, reference being had to the accompanying drawings, forming part thereof.

In the drawings, Figure 1 is a front side view, and Fig. 2 shows an opposite side elevation, of a member of a pair of shears embodying my novel design.

As shown in the drawings, the leading or material feature of my design consists in the graceful shape of a member of a pair of shears, the same comprising a handle and blade portion, as shown.

The handle A of the member consists of an oval oblong opening B, formed between the concave inner side wall C and the convex

outer wall D, as clearly appears in the drawings. The rear end of the handle B is provided with an inwardly-projecting corner E. ²⁵ The shank of the handle is in the form of a reversed curve F and unites the blade with the handle, so that the latter is substantially on a line central therewith. One side of the blade G is plain or smooth, as shown in Fig. ³⁰ 2, and the opposite side is beveled, as seen at II. The blade is pointed and contains a central hole I.

Having thus described my invention, what I claim, and desire to secure by Letters Patent, is—

The design for a member of a pair of shears, as herein shown and described.

Signed at Bridgeport, Fairfield county, Connecticut, this 10th day of October, A. D. 1899. ⁴⁰

JOHN J. ALVORD.
